UNITED STATES PATENT OFFICE.

ALFRED JAMES AMBROSE, OF NORTH YAKIMA, WASHINGTON.

WIRE-APPLYING TOOL.

1,190,075.

Specification of Letters Patent.

Patented July 4, 1916.

Application filed August 24, 1915. Serial No. 47,101.

To all whom it may concern:

Be it known that I, ALFRED J. AMBROSE, a citizen of the United States, and a resident of North Yakima, in the county of Yakima 5 and State of Washington, have invented certain new and useful Improvements in Wire-Applying Tools, of which the following is a specification.

My invention is an improvement in wire 10 tiers and cutters, and the invention has for its object to provide a combination tool of the character specified, especially designed for facilitating the securing together of bundles of box-shook ends, wherein the tool is 15 arranged to twist the ends of a piece of wire drawn around the bundle and to sever the piece from the remaining wire after the twist or knot has been formed.

In the drawings: Figure 1 is a perspective 20 view of the tool in use; Figs. 2, 4 and 5 are sections on the lines 2—2, 4—4, and 5—5 respectively, of Fig. 1; Fig. 3 is a partial rear view on an enlarged scale; Fig. 6 is a partial sectional view at right angles to Fig. 25 2, and Fig. 7 is a perspective view of a portion of a bundle of shooks showing the twist.

In the present embodiment of the invention the tool consists of sections 1 and 2, pivotally connected together, both of the 30 sections being substantially cylindrical casings, and pivoted together at the end of the section 1 and near the end of the section 2, by means of a rivet 3. The inner end of the section 2 is cut away on the under side, and 35 this end of the section is shaped to form side walls and a top wall. The upper end of the section 1 of the tool is received between the side walls so formed, at the inner end of the cut away portion, and the rivet 3 passes 40 through the walls and the top of the section 1 to pivotally connect the sections.

A plunger 4 is mounted to reciprocate in the section 1, and this section has a longitudinally extending slot 5 at the plunger. A 45 link 6 connects the plunger 4 with the section 2 in a manner to be presently described, and a coil spring 7 is arranged between the upper end of the plunger and the rivet 3, the spring acting normally to press the plunger 50 downward, while the plunger is moved upward by means of the link 6.

The link 6 has an annular lug 8 at its lower end which passes through the slot 5, and engages a transverse recess 9 in the plunger, and the lug is pivoted to the plunger by 55 a rivet 10. A block 11 is arranged between

the side walls of the section 2 at the inner end thereof, and on the opposite side of the rivet 3 from the body of the section 2, and this block as shown more particularly in 60 Figs. 2 and 4, is rabbeted at one side.

The upper end of the link 6 fits within the rabbeted portion, as shown in Fig. 4, and a rivet 12 is passed transversely of the said upper end and the block to pivotally connect 65 the block to the link. At its upper end the link 6 has an outwardly extending tooth or blade 13, and the block 11 is provided at its lower end with a similar tooth or blade 14, but facing in the opposite direction to that 70 of the link. These blades 13 and 14 are cutting blades, for cutting the wire, and it will be noticed that the adjacent plane faces of the blades are beveled in the same direction, to form cutting edges at the adjacent faces 75 of the blades.

It will be evident that when the blade 14 is moved past the blade 13, as shown in Fig. 2, with the wire between the blades, the wire 80 will be cut.

The pivot pin or rivet 12 before mentioned passes through the link 6, the rabbeted portion of the block 11, and the side walls of the section 2, thus not only pivoting the link to the block, but also assisting in holding the 85 block to the section 2, and the block is further held to the section by other rivets 15.

It will be evident from the description, that when the outer end of the section 2, which is the handle portion, is depressed as 90 shown in Fig. 2, the plunger 4 will be lifted, and this plunger is reduced at its lower end and is cut away to provide a laterally extending pin 16.

A sleeve or ferrule 17 is threaded onto the 95 lower end of the section 1, and this pin 16 when in the position of Fig. 2, extends diametrically of the ferrule.

In operation, the shook ends, designated at 18, are arranged in a bundle, and the wire 100 19 is passed around the bundle, with the ends lapping, as shown in Figs. 1 and 6. The section 1, which is the body of the handle, is placed as shown in Fig. 1, and the spring 7 will hold the parts in the position shown 105 in that figure. It will be understood that the bundle is at this time in a press or clamp, the said clamp being so arranged that the wire 19 may be passed around the bundle without interfering with the clamp. The 110 pin 16 is engaged beneath the lapping ends of the wire, as shown in Figs. 1, 2 and 6, the

spring normally holding the plunger in its lowermost position, and in this position the pin 16 will be extended below the lower end of the section 1. The ends of the wire 19 are held loosely in the position shown in Fig. 1, between the thumb and finger of the left hand of the operator, his right hand grasping the tool. The operator now presses downward on the outer end of the handle portion or section 2, and a loop of the overlapping ends will be drawn up into the ferrule, as shown in Fig. 6. This movement takes up slack in the wire, drawing that portion of the wire encircling the bundle taut. The operator now twists the tool on the central axis of the section 1 or body portion to form the twist 20 shown in Fig. 7. He can twist the wire as tightly as may be necessary, a single complete turn, however, being sufficient. During the twisting the handle portion of the tool is held depressed, that is in the position of Fig. 2. When the twist has been formed, the operator releases the handle portion and the spring 7 immediately forces the plunger downwardly, permitting the pin 16 to be disengaged from the loop of wire formed by the twisting. After the tool has been released, that portion of the wire encircling the bundle may be cut away from the body of the wire on the reel or in the roll, by means of the cutting blades 13 and 14. The wire is inserted between the blades, and the handle portion 2 is swung into the position of Fig. 2. The blades 13 and 14 move past each other, severing the wire, and the tool is ready for another operation.

I claim:

1. A tool of the character specified, comprising a body portion and a handle portion, the body portion being tubular and being pivoted to the handle portion near one end thereof, a plunger mounted to slide in the body portion, a block secured to the handle portion at the end adjacent to the body and on the outer side of the pivotal connection with the body portion, a link connecting the block to the plunger, the body portion having a longitudinal slot and the link having an angular lug extending through the slot and pivoted to the body portion, a spring normally pressing the plunger away from the handle portion, a ferrule detachably connected with that end of the body portion remote from the handle portion, said plunger having the end adjacent to the ferrule cut away to form a pin extending diametrically of the body portion for engaging the wires to be twisted, said link and block having laterally extending blades adjacent to the pivotal connection, the blade of the block being below the blade

of the link when the body portion of the tool is upright, and adapted to move past each other when the handle portion is moved toward the body portion. 65

2. A tool of the character specified, comprising a body portion and a handle portion, the body portion being tubular and being pivoted to the handle portion near one end thereof, a plunger mounted to slide in the body portion, a block secured to the handle portion at the end adjacent to the body and on the outer side of the pivotal connection with the body portion, a link connecting the block to the plunger, the body portion having a longitudinal slot and the link having an angular lug extending through the slot and pivoted to the body portion, a spring normally pressing the plunger away from the handle portion, and a ferrule detachably connected with that end of the body portion remote from the handle portion, said plunger having the end adjacent to the ferrule cut away to form a pin extending diametrically of the body portion for engaging the wires to be twisted. 70

3. A tool of the character specified, comprising a tubular body and a handle pivoted to one end of the body near one end of the handle, a plunger in the body and provided at the end remote from the handle with a lateral pin extending diametrically of the body, a spring normally pressing the plunger away from the handle portion, and a connection between the plunger and the handle for constraining the plunger to move toward the handle when the outer end of the handle is moved toward the body, and coöperating cutting blades in connection with the handle and the plunger and moved past each other by the movement of the outer end of the handle toward the body. 90

4. A tool of the character specified, comprising a tubular body and a handle pivoted to one end of the body near one end of the handle, a plunger in the body and provided at the end remote from the handle with a lateral pin extending diametrically of the body, a spring normally pressing the plunger away from the handle portion, and a connection between the plunger and the handle for constraining the plunger to move toward the handle when the outer end of the handle is moved toward the body, and a ferrule detachably connected with that end of the body remote from the handle. 100
